UNITED STATES PATENT OFFICE.

SHERROD RIDDEL, OF SPRINGFIELD, ILLINOIS, ASSIGNEE OF ONE-FOURTH TO WARREN W. ALBRIGHT AND ONE-FOURTH TO WILLIAM LAHNERS, BOTH OF DECATUR, ILLINOIS, AND ONE-FOURTH TO JAMES J. GRAHAM, OF SPRINGFIELD, ILLINOIS.

AUTOMATIC SWITCH STAND.

Application filed March 15, 1922. Serial No. 543,978.

To all whom it may concern:

Be it known that I, SHERROD RIDDEL, a citizen of the United States, residing at Springfield, in the county of Sangamon and State of Illinois, have invented certain new and useful Improvements in Automatic Switch Stands, of which the following is a specification.

This invention relates to automatic switch stands and more particularly to a vehicle actuated switch mechanism of simple construction.

The primary object of the invention is to provide a switch stand of this character which will be much more simple in construction than any of the switches now generally employed in coal mines and on railroads, and which will be durable and efficient in operation so that actuation of the switch will be assured when the operating mechanism is actuated.

A further object of the invention is to provide a mechanism which will assure longitudinal movement of the operating rod when the mechanism is placed in motion.

Other objects of the invention will appear upon consideration of the following detail description and accompanying drawings, wherein:

30 Figure 1 is a perspective view of the device constructed in accordance with my invention,

Figure 2 is a horizontal section therethrough taken approximately on the line 35 2-2 of Fig. 1, to show the interior construction.

Referring to the drawing by numerals, the supporting structure 1 consists of a base plate 2 adapted to be mounted in position adjacent the switch rails. This base plate supports a housing 3 which is in the form of a sleeve having a central bore 4. The sleeve, it will be noted, is disposed horizontally so that the bore 4 extends horizontally through the sleeve to receive a horizontally disposed operating screw 5 having worm threads 6 cut therein. The operating screw 5 is considerably longer than the sleeve 3 and the interior of the sleeve or bore 4 is provided with corresponding screw threads whereby the worm screw 5 will mesh with the threads on the interior of the sleeve 3. In this manner the screw 5 forms a longitudinally movable actuating member for the switch

mechanism. An automatic operating lever 7 is adapted to be fixed to one end of the screw or actuating member 5. This lever 7 is provided with a sleeve 8 fitting over an extension 9 on the end of the screw, the sleeve being rigidly secured to the extension 9 by a fastening bolt 10 passing transversely through the sleeve 8 and extension 9 as shown in Fig. 2. This sleeve 8 also serves as a coupling member to provide a swivel joint for the operating rod 11. The sleeve 8 is provided at one end with an opening 12 smaller than the interior bore of the sleeve and the operating rod 11 is extended through the opening 12 and is provided on its inner end with a head 13 thus preventing withdrawal of the operating rod 11 from the sleeve but permitting the sleeve to freely rotate with the screw 5 without rotating the rod 11. The head 13 is removably attached to the rod 11 by any suitable mechanical expedient to permit the parts to be readily assembled. The free end of the operating rod 11 is provided with any suitable connection 14 whereby the operating rod may be attached to the switch rail. The opposite end of the screw 5 is equipped with a hand lever 15 carrying a weight 16 to assure quick operation of the device when the lever 7 is engaged by a passing motor or vehicle. The frictional engagement of the operating screw with the worm threads in the sleeve 3 is tight enough to maintain the lever 15 in its vertical position until the actuating lever 7 is forcibly moved to either side. The operation of the device will be readily apparent from the above description, but it should be noted that the mechanism is arranged adjacent the rails over which the motor or vehicle travels so that a trip or other extension on the motor or vehicle will engage the lever 7 swinging the lever and thus turning the actuating member 5. Since the sleeve 3 is stationary it will be obvious that the screw 5 will longitudinally move by virtue of its screw 100 threaded connection with the sleeve 3 thus causing the lever 15 to be tilted sufficiently to cause the weight 16 to complete the rotary motion of the screw 5. This action longitudinally moves the screw 5 through the 105 housing or sleeve 3 and thereby imparts longitudinal movement to the operating rod 11 for imparting the necessary movement to

the switch point as will be readily understood.

Minor changes may be made in the details of construction without departing from the spirit of the invention or the scope of the claims hereunto appended.

What is claimed is:—

1. A switch stand comprising a stationary screw threaded sleeve, a screw-threaded actuating member engaged with the threads in said sleeve, an operating rod connected to said actuating member whereby said rod will be actuated longitudinally when said actuating member is turned in said sleeve,
- 10 15 means fixed to said actuating member to be forcibly engaged for imparting an initial rotary motion to said actuating member, and a weighted lever mounted on the end of the actuating member for continuing the 20 rotary movement of said actuating member after the initial impetus has been imparted to said means.

2. A switch stand comprising a station-

ary screw threaded sleeve, an actuating member provided with screw threads engaged with the screw threads on the said sleeve, an actuating lever, a coupling sleeve attached to the actuating lever and rigidly fixed to one end of the screw threaded member, an operating rod, one end of the sleeve being provided with a relatively small opening to receive one end of the operating rod, the inner end of the said rod being equipped with a head to prevent withdrawal of the said operating rod from the said sleeve whereby the said sleeve will impart longitudinal movement to the said operating rod when the actuating member is moved, a weighted lever mounted on the end of the said actuating member opposite to the said sleeve for continuing the rotary motion of the said actuating member after the initial impetus has been received by the first mentioned actuating lever.

In testimony whereof I affix my signature.
SHERROD RIDDEL.
